(Cl. D34—15)

Fig. 1.

Fig. 2.

To all whom it may concern:

Be it known that I, Thomas L. Hayden, a citizen of the United States, and resident of Inglewood, in the county of Los Angeles and State of California, have invented a new, original, and ornamental Design for a Child's Toy Support, of which the following is a specification, reference being had to the accompanying drawing, forming a part thereof;

Figure 1 is an elevational view of a child's toy support showing my new design; and

Figure 2 is a fragmentary perspective view on an enlarged scale.

I claim:

The ornamental design for a child's toy support, substantially as shown.
